UNITED STATES PATENT OFFICE.

CHARLES A. SHIELDS, OF MONTREAL, QUEBEC, CANADA.

PAPER-CLIP.

No. 862,025.

Specification of Letters Patent.

Patented July 30, 1907.

Application filed June 16, 1906. Serial No. 322,052.

To all whom it may concern:

Be it known that I, CHARLES A. SHIELDS, a citizen of the United States of America, residing at Montreal, in the Province of Quebec and Dominion of Canada, have invented new and useful Improvements in Paper-clips, of which the following is a specification.

This invention relates to spring clips or fasteners of that type in which the clip or fastener is made of a single piece of spring wire bent into form and designed for 10 fastening sheets of paper or other materials, folded packages and similar articles.

The object of the invention is to provide a clip of this character which is bent in such form as to adapt it to be conveniently, rapidly and economically manufactured, 15 which may be readily and easily applied without injury to the sheets of paper, which will securely clamp the sheets together without liability of tearing or wrinkling the sheets, and which by reason of its peculiar, yet simple, formation presents a greater number of clamping 20 portions to insure a firmer grip upon the sheets of paper without rendering the clip unduly stiff and difficult to manipulate.

In the accompanying drawing.—Figure 1 is a plan view of a clip or fastener embodying my invention. 25 Fig. 2 is a similar view of the clip on an enlarged scale and illustrating its mode of application. Fig. 3 is an edge view of the clip.

As shown in the drawing, the clip is formed of a single wire of a suitable size or gage, and comprises a head or 30 cross bar 1 and coöperating clamping jaws 2 and 3. The head or cross bar 1, which is preferably straight and lies against or adjacent to the edges of the sheets to which the clip is applied, is formed by the central portion of the wire. At the ends of the head 1 the wire is 35 turned or bent at right angles from one side of the head, as shown at 4, and is thence continued to form the clamping jaws. Each jaw comprises a pair of arms 5 and 6, the arms 5 of the jaws being formed by continuing the wire from the bends 4 in such a manner that the arms 40 project convergently in opposite directions and cross at the point 7. At their outer or lower ends, the arms 5 are joined to the lower ends of the arms 6 by bending the wire outwardly, as illustrated at 8. The arms 5 extend obliquely to what may, for convenience, be 45 called the central longitudinal line of the clip, *i. e.*, a line intersecting the center of the head and crossing point of the arms 5, while the arms 6 project in parallel relation to each other and to such central longitudinal line of the clip and extend upwardly from the bends 8 50 and terminate at their free ends adjacent the under side of the head or cross bar 1. By this arrangement, the arms 6 cross the arms 5 at the points 9, and each jaw is caused to have approximately the form of an isosceles triangle, one side of which is formed by the head or cross 55 bar 1 common to both jaws. The bends 4 are offset or

projected at an oblique angle to the bar 1, as clearly shown in Fig. 3, to throw the arms 5 out of direct alinement with said bar and to bring the arms 6 into alinement therewith, whereby the free ends of the said arms 6 normally lie in the spaces formed by the bends 4 and 60 beneath the bar 1. By this arrangement, the free ends of the arms 6 are housed or shielded, thus preventing the projection of points or surfaces which are liable, in the operation of handling the clip, to injure the hands or tear the papers, clothes or other articles with which 65 the clip comes in contact. The bends 4 and 8 impart a torsional twist to the wire, whereby the jaws are adapted by their spring action to grip the sheets of paper firmly between them.

In applying the clip, it is held in a plane at an angle 70 to the sheets of paper, with the edges of the sheets lying in the angle at the point 7. When the clip is turned so that its front and back portions bear respectively upon the corresponding surfaces of the sheets of paper the resulting strain will open the clamping jaws and permit 75 the clip to be pushed down upon the sheets until the edges thereof abut against the straight cross bar or head 1 between the bends 4 and lie snugly in the spaces formed by said bends. When thus applied, the jaws will operate to press or clamp the sheets of paper against 80 each other at the contact points 7 and 9, while the free ends of the jaws 6 will also hold the edges of the sheets against the bends 4. Hence, the sheets of paper will be clamped at a plurality of widely separated points, 85 thus fastening the sheets firmly and securely together.

Owing to the simple form of the clip and its freedom from a crossed relationship of the arms 6 *per se*, the clip may be much more readily and easily manipulated and is less liable to tear, wrinkle or otherwise injure or mutilate the clamped sheets of paper. Furthermore, 90 the construction described permits of the more convenient, rapid and economical manufacture of the device, and at the same time affords a greater number of clamping points and a more powerful gripping action.

Having thus described the invention, what is claimed 95 as new, is:—

1. A clip of the character described, comprising a single piece of wire bent to form a head or cross bar, thence bent to form short right-angled portions and continued to provide upon one side of said cross bar crossing primary arms projecting convergently continuously from their points of junction with said right-angled portions obliquely to the center line of the clip, and finally bent to form straight terminal arms extending parallel with the center line of the clip from the outer ends of the primary arms to the points of junction of said primary arms with the right-angled portions, the crossing point of the said primary arms being so arranged that the pairs of primary and terminal arms provide coöperating jaws, each having approximately the form of an isosceles triangle, one side 100 of which is formed by the head or cross bar common to both jaws.

2. A clip of the character described formed from a single piece of wire comprising a head or cross bar and a pair of opposing jaws, the jaws comprising primary arms connected with the cross bar and arranged in crossed relation, and terminal arms extending from the outer ends of said primary arms in parallel relation to points adjacent the points of junction of the head with the primary arms, the wire being offset at such points of junction to bring the ends of the terminal arms in the plane of the cross bar.
- 5 3. A clip comprising a piece of spring wire bent to form a cross bar or head 1 and jaws 2 and 3 connected with the cross bar by the offset bent portions 4, the jaws being formed by a continuation of the wire from the bends 4 to provide convergently arranged crossing arms 5 extending obliquely to the center line of the clip and terminal arms 6, said arms 6 being arranged in parallel relation with each other and with the center line of the clip and extending across the upper ends of the arms 5 into the spaces formed by the bends 4 below the head 1, the head 10 and jaws forming the base and sides of a double triangular clip, substantially as described.
- 15 4. A clip of the character described comprising a single piece of wire bent to form a straight head or cross bar 1, thence bent to form short right-angular portions 4 at the ends of the bar, thence bent to form primary arms 5 projecting convergently in opposite directions and crossing at the point 7, whereby said arms extend obliquely to the center line of the clip from said right-angular portions 4, and finally bent outwardly and upwardly to produce straight terminal arms 6 extending parallel with the center line of the clip from the outer ends of the primary arms with their free ends crossing said primary arms adjacent the points of junction of said primary arms with the right-angular portions 4 and lying on the inner sides of the latter.
- 20 In testimony whereof, I affix my signature in presence of two witnesses.

CHARLES A. SHIELDS.
